UNITED STATES PATENT OFFICE.

COLDWELL C. BEEBE, OF RACINE, WISCONSIN.

ARTIFICIAL TOOTH.

1,212,885.

Specification of Letters Patent. Patented Jan. 16, 1917.

Application filed September 8, 1915. Serial No. 49,441.

To all whom it may concern:

Be it known that I, COLDWELL C. BEEBE, a citizen of the United States, and resident of Racine, in the county of Racine and State 5 of Wisconsin, have invented certain new and useful Improvements in Artificial Teeth; and I do hereby declare that the following is a full, clear, and exact description thereof.

This invention relates to new and useful 10 improvements in artificial teeth and is particularly directed to the provision of means for attaching porcelain facings of artificial teeth in a manner whereby they may be detached and replaced upon becoming broken 15 or for any other desired reason.

A common disadvantage in the method of attaching porcelain facings is that such methods of attachment as have been heretofore employed have a tendency to chip or break the facings.

It is therefore an object of the present invention to provide a means for attaching porcelain facings whereby the tendency to breakage of said facings is lessened by providing a firm seat for said facings on the 25 backing.

With the above and other objects and advantages in view, the invention resides more particularly in the novel combination, arrangement and formation of parts more particularly hereinafter described and particularly pointed out in the appended claims.

Reference is had to the accompanying drawings wherein similar characters of 30 reference designate corresponding parts throughout the several views and in which:

Figure 1 shows a front elevational view of the improved facing and backing members connected with a crown cap member 40 and attached to the natural root of a tooth; Fig. 2 is a side elevation of what is shown in Fig. 1; Fig. 3 is a rear elevation; Fig. 4 is a vertical sectional view taken centrally through the tooth on the line 4—4 of Fig. 1; Fig. 5 is a transverse sectional view taken on 45 the line 5—5 of Fig. 4; Fig. 6 is a perspective view of the porcelain facing member, looking downwardly from the rear portion thereof; Fig. 7 is a front elevation of the improved backing member; Fig. 8 is a detailed 50

sectional view showing the cap member of the crown; Fig. 9 is a top plan view of a modified form of backing member provided with means whereby it may be more readily secured to the crown cap; Fig. 10 is a vertical sectional view taken through this modified backing member on the line 10—10 of Fig. 9.

Referring now more particularly to the accompanying drawings, 5 designates in the first four figures thereof, the natural root of a tooth and 6 designates the crown cap member which is secured onto said root by the pivot pin 7 which extends into the nerve canal of the tooth and it is cemented as 65 shown at 8. This is the usual method of attachment for artificial teeth, but in the ordinary structure the backing which engages and holds the porcelain facing is made integral with the cap member. In my construction however I find it expedient to provide a separate backing designated in the drawings at 9, which is adapted to be welded to the cap member after making of such cap member and which is adapted to receive the 70 improved facing member 10.

Taking up now the specific shape of the facing member, it includes a labial face *a*, a lingual face *b* and an inner face *c* which abuts against the backing member 9 to form 75 a member substantially triangular in side view. The medial and distal faces of the facing member are provided with longitudinal grooves 11 which taperingly increase in depth and size toward the face *c*, the adjacent sides of said grooves being substantially parallel to the labial face *a* so that by their tapering enlargement they intersect and taperingly reduce the face. The face *c* is provided adjacent its juncture with the face 80 *b* with a transversely extending groove 12 which has its ends communicating with the grooves 11 and curved toward the juncture of the faces *a* and *b* in accordance with a corresponding curvature of the meeting edge 85 of the faces *b* and *c*, this curvature being caused by the tapering reduction of that portion of the tooth by reason of the grooves 11. By so curving the groove 12, it has a bearing 90 surface approximately equal to the combined 95 100

bearing surfaces of the grooves 11 whereby strain imparted on the tooth is equally distributed. This is an exceedingly important feature. The abutting face *c* is concaved 5 transversely of the tooth. The grooves 11 terminate short of the outer corners of the side faces.

To engage the face *c* of the facing member 10, the backing member 9 is of substantially 10 triangular side elevation and has formed at the sides of its abutting or front face *d* a pair of flanges 13 which project forwardly of said face and are provided on their inner faces with flanges 14 tapered to fit in the 15 tapered grooves 11. The front face of the backing is also provided adjacent its junction with the lingual face with an arcuate rib 15 which seats in the groove 12 of the facing, and the front face of the backing 20 is formed of convex shape to fit the concave face *e* of the facing. The face *e* and the medial and distal faces and flanges 13 of the backing coincide with and form continuations of the lingual face *b* and the medial 25 and distal faces of the facing. The top face *f* of the backing is welded or otherwise secured to the crown cap 6.

The structure shown in Figs. 1 to 8 of the drawings is particularly adapted for use 30 in connection with incisor teeth, it being with this type of teeth that the greatest difficulty is encountered in applying porcelain facings. For other types of teeth, the same general structure is applied except that 35 more opportunity is had and taken advantage of to increase the size of the grooves whereby greatly lessened liability of said grooves causing the facing to chip may be had.

40 Figs. 9 and 10 show a further modification of the backing member. In this form of the invention, the body of the backing member is made narrower, and the flanges 13 of the backing members heretofore shown 45 carry ribs 14' which extend parallel to the inner face *d* of the backing, so that they are projected forwardly of the backing and, being converged, may carry a correspondingly formed facing member of greater width 50 than the usual facing member and which is adapted to project forwardly past the backing member so that none of the backing member is exposed at the front of the tooth. To facilitate securing this backing member 55 to the crown cap, the upper edge portions of the rear face *e* and the side faces are offset inwardly and at the lower edge of these inwardly offset portions is formed a horizontal continuous groove 19 in said rear 60 and side faces. In tentatively applying the backing member to the crown cap to determine its proper position to hold the facing member in proper alignment with the other teeth, this groove 19 and the offset portions

of the rear and side faces are adapted to 65 hold wax which forms the temporary securing means, and in permanently securing the backing to the cap, fused gold or other securing medium is disposed in the groove and over the inwardly offset portion of the faces whereby the backing member may be securely attached to the crown cap member. Although the grooves 19 and 70 the offset portions of the lingual and the medial and distal faces are shown as applied to a certain modified form of backing member, it will be appreciated that this structure may be readily associated with any other form of the invention, including the preferred form shown more particularly in 75 Figs. 1 to 7 inclusive of the drawings.

In assembling and applying the structure described to the natural root of a tooth, the cap member 6 is made by the dentist in the usual manner to properly fit the root. The 80 backing member 9 is then fused onto the cap member and the porcelain facing is cemented in place on the backing. By the particular arrangement of applicant's face 85 *c* and the grooves 11 and 12, it is seen that a maximum amount of bearing surface is had between the facing and the backing without excessively weakening the facing or tending to produce a chipping of portions thereof. This increased bearing face 90 greatly facilitates cementing the facing in place. Should the facing be broken, it can be readily removed by forcing loose the cement connection and a new facing may be applied without disturbing the attachment 95 of the backing to the crown cap.

I claim:

1. An artificial tooth comprising a facing member and a backing member having meeting faces intersecting the labial and lingual faces and disposed at an acute angle to the base face of the tooth, the facing member being provided in its medial and distal faces with grooves extending toward and taperingly enlarged toward the base face and being further provided in said base face rearwardly of the said grooves with a transverse groove having its sides extended laterally in the medial and distal faces and having its bottom curved whereby the bearing surface of the transverse groove approximates the combined bearing faces of the medial and distal face grooves, and portions carried by the backing member to engage in said grooves whereby strain incident to longitudinal pressure on the tooth, is equally distributed in the transverse groove and in the medial and distal grooves. 110

2. As an article of manufacture, a backing member having its top face adapted for 115 securement to a crown cap member, the adjacent portions of its labial and its medial and distal faces being inwardly offset and

provided with a curved horizontal groove in the county of Milwaukee, and State of forming an under cut in said offset face Wisconsin, in the presence of two witnesses. portions and said backing member being. formed for attachment of a facing member thereto.

In testimony that I claim the foregoing I have hereunto set my hand at Milwaukee,

COLDWELL C. BEEBE.
